REFRIGERATOR

Arthur C. Shuart, Rockford, Ill., assignor to
 Servel, Inc., New York, N. Y., a corporation of
 Delaware

Application April 12, 1937, Serial No. 136,299

4 Claims. (Cl. 20—69)

My invention relates to refrigerators, and has for its object to provide an improved refrigerator door structure.

The objects and advantages of the invention will be more fully understood from the following description taken in connection with the accompanying drawing forming a part of this specification, and of which Fig. 1 is a front elevation of a refrigerator cabinet provided with a door embodying my invention; Fig. 2 is a rear elevation of the door illustrated in Fig. 1; Figs. 3 and 4 are fragmentary sectional views taken on lines 3—3 and 4—4 of Fig. 2; Fig. 5 is a bottom plan view of a separate corner piece of the gasket shown in Fig. 2; Fig. 6 is a sectional view taken on line 6—6 of Fig. 5; and Fig. 7 is an enlarged sectional view on line 7—7 of Fig. 2.

Referring to Fig. 1, I have shown a refrigerator comprising a cabinet 10 having a thermally insulated storage space 11 into which access may be had by a door 12 hinged to the front of the cabinet. Within the storage space 11 is arranged a cooling element 13 of refrigeration apparatus for producing cold and maintaining the space 11 at a desired low temperature.

The door 12 includes outer and inner wall members 14 and 15 which may be maintained in spaced relation by a door frame 16, for example, or in any other suitable manner. The space between the outer and inner wall members 14 and 15 is filled with a suitable heat insulating material 17. The outer wall member 14 extends beyond the inner wall member 15 and is bent back upon itself to form a ledge 18 which overlies the front exterior wall of the cabinet 10 when the door 12 is closed.

A breaker or trim strip extends about the periphery of the door and includes strips 19 positioned along the sides of the door with the longitudinal edges thereof overlying the edges of the outer and inner wall members 14 and 15. Each of the strips 19 is secured in any suitable manner, as by screws 20, for example, to the periphery of the door. At the round corners of the door the ends of adjacent strips 19 are joined by curved angle members 21 which are secured, as by small pegs or screws 22, for example, to the periphery of the door 12. The extreme ends of the strips 19 are slightly reduced in width, and the corner members 21 overlap these end portions of the strips. The strips 19 and curved angle members 21 may be formed of suitable material, such as the material commercially known as Bakelite, so that the inside of the door will be neat in appearance.

A multi-section gasket is provided at the ledge 18 for effectively sealing the door 12 when it is locked in its closed position. The multi-section gasket comprises corner pieces 23 located at the corners of the door and straight pieces 24 extending between the corner pieces 23. The corner and straight pieces 23 and 24 of the gasket are preferably formed of resilient material, such as rubber, for example, the corner pieces 23 preferably being molded into the desired shape with a radius of curvature which will conform to the contour of the round corners of the door.

The corner pieces 23 are formed with an intermediate flat portion 25, an inner inclined edge portion 26, and an outer edge 27 which is curved and semi-circular in section, as shown in Figs. 3 and 6. The curved outer edge 27, which serves as a hollow striking bead, is provided with a plurality of spaced walls or supporting webs 27'. In order that the corner pieces 23 can easily be located in position at the corners of the ledge 18, the flat intermediate portions 25 are provided with a plurality of projections or buttons 28. The corner pieces 23 are secured in position by pressing the buttons 28 through openings at the inner surface of the ledge 18. With the corner pieces 23 in position at the corners of the ledge 18, the striking beads 27 along their entire length bear uniformly against the extreme outer edge of the ledge with the corner pieces conforming to the contour of the round corners of the door 12. The inner inclined edge portions 26 of the corner pieces 23 bear against the inclined flange of the outer wall member 14 which extends toward the inner wall member 15, and the outer edge portions of the curved corner angle members 21 overlie and bear against the inner edge portions 26 of the corner pieces 23.

The straight pieces 24 of the gasket, which may be formed of extruded rubber, are similar in cross-section to the molded corner pieces 23 and are provided with a hollow striking bead 30 along the outer longitudinal edges thereof. The inner inclined edge portions of the straight pieces 24 also bear against the inclined flange of the outer wall member 14, as shown at 32 in Fig. 4, and the strips 19 overlie the inclined inner edges of the straight pieces 24 and retain the latter in position. The ends of the straight pieces 24 and the ends of the curved corner pieces 23 are contiguous to each other and in abutting relation, and are secured together in any suitable manner, as by small staples or U-shaped clips 31. The corner pieces 23 and straight pieces 24 preferably are of such length that the force applied to

the striking beads when a door is closed will effectively seal the joints between the separate pieces of the gasket.

By providing a door having a multi-section 5 gasket and breaker strip of the character just described, the assembly of the door is facilitated considerably. Since the corner pieces 23 are molded to conform to the contour of the round corners of the door 12, crimping of the gasket at 10 the corners is avoided and effective sealing is obtained about the entire periphery of the door.

While I have shown and described a particular embodiment of my invention, such variations and modifications are contemplated as fall within the 15 true spirit and scope of my invention, as pointed out in the following claims.

What is claimed is:

1. A gasket for the corner of a refrigerator door, said gasket being molded and formed of 20 resilient material, such as rubber, and having a flat portion with curved edges and provided with a recessed striking bead at the outer edge, and a ledge on the inner edge at an angle with the flat portion and adapted to be secured and hidden by 25 a part of the refrigerator.

2. A gasket for the corner of a refrigerator

door, said gasket being molded and formed of resilient material, such as rubber, with the outer and inner edges thereof curved or rounded, and having a flat portion provided with a striking bead at the outer curved edge thereof and a lip 5 on the inner curved edge extending at an angle with said flat portion and adapted to be secured and hidden by a part of a refrigerator.

3. For use with a refrigerator having a door with straight sides and curved corners, a gasket 10 comprising straight strips and preformed corner pieces of molded rubber, said strips and corner pieces having a flat portion with a bead on one edge and a securing projection on the opposite edge at an angle to the flat portion, both edges 15 of said corner pieces being curved substantially concentrically.

4. A corner gasket for use in refrigerator cabinet construction, said gasket being molded and formed of resilient material, said gasket having similarly curved inner and outer edges with the inner edge provided with an angularly disposed flange by means of which the gasket may be secured in position, and the outer edge being provided with a striking bead. 20 25
